George Sharp, of Philadelphia, Penn.
Letters Patent No. 1880-Dated Jany. 5th 1864.

Design for a Spoon Handle.

The schedule referred to in these Letters Patent and making part of the same.

To all whom it may concern:

Be it known that I, George Sharp, of the City of Philadelphia, in the State of Pennsylvania, have invented or produced a new and original Design for the ends of the handles of spoons, and such other articles as are made by silver-smiths generally for table use and require shank handles; and I do hereby declare that the following is a full and exact description of the same, reference being had to the accompanying drawing, making a part of this specification, and to the letters of reference marked thereon.

The nature of my invention or production consists in finishing the extreme outer ends of the shank handles of spoons, ladles, scoops, shovels, knives, forks, crumb-scrapers, call-bells, nut-picks, and such other articles of table use as require shank handles, each in the ornamental globular form herein described and shown.

The drawing represents a chicken salad spoon having my ornamental design - the ball or sphere A applied thereto.

The ball A, is, in this instance, attached to the end of the handle a', by means of a neck piece a², consisting of a cavetto, scotia, and fillets; and has attached to its opposite side a very much smaller ball a³,

The surface of the ball or sphere A, is also represented in the drawing as being smooth or even, but it is my intention to make the surface either plain or ornate, as may be preferred.

Having thus fully described and set forth my invention or production:

Dec 1880

What I claim as new and desire to secure by Letters Patent is, The globular finish consisting of the parts A, a, & a', as an ornamental design for the ends of the handles of the articles of table use specified.
